UNITED STATES PATENT OFFICE.

LEO H. WISE, OF NEW YORK, N. Y., ASSIGNOR TO WISE BROTHERS, OF NEW YORK, N. Y.,
A FIRM.

UNION UNDERGARMENT.

No. 904,892.

Specification of Letters Patent.

Patented Nov. 17, 1908.

Application filed August 31, 1908. Serial No. 450,936.

To all whom it may concern:

Be it known that I, LEO H. WISE, a citizen of the United States, residing at New York city, in the county of New York and State of New York, have invented certain new and useful Improvements in Union Undergarments, of which the following is a specification.

This invention relates to a union-suit undergarment. Garments of this type comprise a shirt or body-part and the drawers or legs-part combined in one suit.

One object of the present invention is to provide a union-suit whose front pieces of woven fabric shall be inelastic in the vertical direction, but whose back shall be elastic in the vertical direction; and another object is to provide means at the shoulders and at the front which shall be both elastic and also adjustable so as to make the garment easy to the wearer and also to adapt one garment for persons of different height.

The invention is illustrated in the accompanying drawing in which,—

25 Figure 1 is a front view of the garment. Fig. 2 is a view of the side of the garment and shows the joinder of the end of the elastic back-band with the inelastic cloth fabric of the front. Fig. 3 is a back view, and 30 Fig. 4 shows the upper part of the back body piece laid flat.

The front upper body or shirt portions, 1, comprises also integral front leg-portions, 2. These two front portions, 1, 2, have free upper ends, 3, at the shoulder and therefrom the one integral piece of fabric extends downward to the lower edge, 4, of the leg.

The entire front of the garment is divided or open along a central vertical line, 6, from 40 the neck, 7, to the crotch, 8, and buttons, 9, and button-holes are employed to close and fasten the two parts of said open front.

The garment is shown armless although this is immaterial, and has only arm-openings, 10. A vertical seam, 11, is at two sides of the garment and extends from the pit or the lower part of arm-opening, 10, downward to the lower edge, 4, of the leg and said two side seams unite the front and 50 back portions. It will be seen the entire front is composed of two pieces of ordinary woven fabric both of which are free at the shoulder and extend from the said upper free end, 3, to the lower edge of the leg, and said

two front pieces are comparatively inelastic in the vertical direction. 55

The back of the union garment comprises four pieces, namely, a body-piece, 12, and the two leg-pieces, 13, which are inelastic, being ordinary woven fabric, and the elastic back-band, 14, which connects the body-piece with the two leg-pieces. The single back body-piece, 12, has at each shoulder a strap, 20. When the back piece is laid flat the two straps point away from each other, as seen 65 in Fig. 4. Each strap has an insert, 21, of elastic material, and a tapered extremity, 22, that is provided with a plural number of button-holes which engage with buttons, 23, on the free upper ends, 3, of the front body-piece. The insert, 21, provides for the shoulders being elastic and the plural number of button-holes provides for an adjustment that will enable the garment to be 70 lengthened or shortened to suit persons of 75 different heights. The back body piece is attached to the two front pieces, 1, by the vertical side seams, 11; the back leg-pieces, 13, are attached to the front leg-pieces, 2, by the outer side-seams, 11, and the inseams, 15. 80 The seat of the garment at the drawers or leg part is open or slotted.

The open-front that is buttoned along the vertical line, 6, continues open under the crotch, 8, and also is open upward vertically 85 at the seat, 16, entirely to the horizontal back-band, 14. The leg-parts at the seat-opening overlap each other, and the outermost lap forms a flap, 17, that has a button-hole which engages with a button, 18. Thus 90 each leg comprises a back part, 13, below the elastic band and the lower-end of the front part, 1, 2.

The back-band, 14, consists of elastic material, such as knit fabric. This elastic band 95 extends horizontally across the back only of the garment and is stitched to and connects between the upper body-piece, 12, and the two back-leg pieces, 13. The ends, 19, of the elastic back-band terminate at the two 100 vertical side seams, 11, and said elastic ends are secured in and by said seams, as seen in Fig. 2.

This garment will be elastic at the shoulders, and also adjustable at the shoulders to 105 lengthen or shorten. It will be inelastic down its entire front including the front-waist, but elastic across the back.

Having thus described my invention what I claim and desire to secure by Letters Patent is,—

1. A union under-garment comprising a front body-portion and leg-portions made of two separate pieces of fabric—each piece extending from the shoulder down to the lower edge of the leg; a single back body-piece from the neck to the waist and united to the front body-portion by two vertical side-seams; two back leg-pieces; and an elastic back-band connecting the said back body-piece with the tops of the two back leg-pieces—said elastic back-band having its ends terminating at and secured in said two vertical side-seams.

2. A union under-garment comprising a front body-portion and leg-portions made of two separate pieces of fabric—each piece having at the shoulder a free upper end and extending therefrom down to the lower edge of the leg; a single back body-piece from the neck to the waist and united to the front body-portion by two vertical side-seams and said back body-piece having at each shoulder a strap provided with an elastic insert and

the extremities of the straps having a plural number of button-holes to engage buttons on the said free upper ends of the fronts; back leg-pieces; and an elastic band extending across the back only.

3. A union under-garment comprising two front-portions each having a free upper end at the shoulder and therefrom extending to the lower end of a leg; a back body-piece from the neck to the waist and provided with shoulder-straps which adjustably connect with the said free upper ends at the front; an elastic band across the back only and attached to the back body-piece; back leg-pieces whose tops are attached to said elastic band, and said garment having a continuous opening extending at the front from the neck down to the crotch, under the crotch, and upward at the seat to said elastic back-band.

In testimony whereof I affix my signature in presence of two witnesses.

LEO H. WISE.
